UNITED STATES PATENT OFFICE.

GEORGE MILLER MARSHALL, OF WINNIPEG, MANITOBA, CANADA.

BUILDING CONSTRUCTION.

1,177,646.

Specification of Letters Patent. Patented Apr. 4, 1916.

Application filed August 31, 1914. Serial No. 859,375.

To all whom it may concern:

Be it known that I, GEORGE MILLER MARSHALL, of the city of Winnipeg, in the Province of Manitoba, Canada, have invented certain new and useful Improvements in Building Construction, of which the following is the specification.

The invention relates to improvements in building construction and the object of the invention is to provide an improved form of building block for double wall construction and also to provide a means for binding the walls formed from the blocks one to the other and to an adjoining structure.

With the above objects in view the invention consists essentially in the arrangement and construction of parts hereinafter more particularly described and later pointed out in the appended claims.

Figure 1 represents a face view of one of the blocks. Fig. 2 represents a plan view of the same. Fig. 3 represents a plan view of a modified form of block. Fig. 4 represents a side view of the tie bar. Fig. 5 represents a vertical sectional view through a portion of a double wall constructed in accordance with my invention and showing one method of fastening it to an adjoining structure. Fig. 6 represents an enlarged detailed vertical sectional view showing the form of fastening appearing in Fig. 5. Fig. 7 represents a vertical sectional view through a double wall constructed in accordance with my invention showing a modified method of fastening the wall to a structure. Fig. 8 represents an enlarged detailed vertical sectional view showing the form of fastening appearing in the modification in Fig. 7.

1 represents a block which is formed from a suitable self-setting composition and is in the nature of a more or less thin rectangular slab. One end of the slab is fitted with an extending V-shaped tongue 2 while the other end is supplied with a complementary V-shaped groove 3. The upper edge of the slab is constructed to present an extending V-shaped tongue 4 while the lower edge thereof is formed with a complementary V-

shaped groove 5.

I wish it to be noticed that the tongues are set back somewhat from the edges of the slab to provide a bearing surface 6.

More or less centrally of the length of the block and at the upper edge thereof I have

formed a cross channel 7 which follows at an even depth the contour of the upper edge of the block.

In using the blocks to build a double wall, they are set one on the other in two rows, 60 providing an air space between them as indicated by the reference letter "A" and when so set up the tongues at the one end and top of a particular block receive the grooves of the adjoining end and top block, 65 while the grooves at the other end and bottom of the said block receive the tongues of the adjoining end and bottom block. Cement or other binding material is inserted between the blocks in the respective walls 70 to effect a bond.

As the walls are being built they are connected at intervals one to the other by tie bars 8, having up-turned ends 8' and 8" designed to be received within the cross channel 7 formed in the upper edges of the blocks. As the blocks are laid on the walls these tie bars are inserted in position and become embedded in the cement forming the bond between the blocks. Upon the cement hardening the two walls are tied effectively by the bars.

In order that the completed double wall may be connected to an adjoining structure 9 such as scantlings or uprights, I supply 85 hangers 10 which are fastened permanently to the uprights by screws 11 and are fitted with outstanding lower ends 10' arranged to be received within the adjoining ends of the cross channels 7 appearing between the blocks of the inner wall. It will be understood that the ends 10' of the hangers are cemented in the channel when the wall is being built in the same manner as are the tie bars. Upon the cement hardening the 90 double wall is effectively fastened to the structure.

It will be seen that in actual practice it is unnecessary to have the cross channel in the blocks used for the outer wall pass completely across the upper edges of the blocks. Such a block, that is, one provided with a short cross channel, is shown in Fig. 3 of the drawing.

Although I have described the double wall as constructed from blocks all provided with channels, still it will be understood that the tie bars are not necessarily inserted wherever the channels appear as it is not necessary to effect a proper fastening and insure 105

110

a proper strength. The builder can insert the tie bars and also the hangers wherever he considers it advisable.

In Figs. 7 and 8 of the drawing I have shown a modified method of fastening the wall to the adjoining structure. In this case the hangers 10 are entirely dispensed with and instead, the blocks are secured to the structure by nails 12, the nails being driven into the structure in an inclined position. In actual practice the nail is driven over the under block before the top block is placed thereon and before the cement or bonding material is applied. The result is that as soon as the bonding material sets the nail is solidly embedded in the bond and accordingly anchors the wall to the structure. In order that the nail can be driven in in the location shown it is necessary to notch the face of the block at the end of the channel as shown at 13.

What I claim as my invention is:—

1. The combination with an inner and outer wall separated by an air space and formed from suitably bonded, substantially rectangular building blocks bearing one on the other and provided on their engaging edges with complementary tongues and

grooves, the tongue carrying edges of the blocks being formed with cross channels of even depth passing across the edge of the block and the tongue, of tie bars connecting the walls and having their ends turned upwardly at an angle to the body thereof and received within the cross channels and embedded within the bond between the blocks.

2. The combination with an inner wall formed from suitably bonded, substantially rectangular building blocks having their meeting edges provided with complementary tongues and grooves and a centrally located cross channel of even depth crossing the tongue bearing edges of the blocks and an adjoining structure, of inclined nails located in the channels and embedded in the bond between the blocks and extending into the adjoining structure and effecting a fastening between the wall and the adjoining structure.

Signed at Winnipeg this 6th day of 50
August 1914.

GEORGE MILLER MARSHALL.
